UNITED STATES PATENT OFFICE

2,529,110

OPHTHALMIC DEVICE HAVING DETACHABLE SHIELD

Edward M. Splaine, Southbridge, Mass., assignor
to American Optical Company, Southbridge,
Mass., a voluntary association of Massachusetts

Application October 1, 1945, Serial No. 619,583

8 Claims. (Cl. 88—41)

1

This invention relates to improvements in ophthalmic devices and more especially in eye protection devices, and has particular reference to a device embodying a transparent shield or lens for protecting the eyes of the wearer from flying particles or the like and which transparent shield or lens may have embodied therein means for varying and controlling the light transmitted thereby. This invention is an improvement over that disclosed by copending application No. 568,282, filed December 15, 1944, now Patent 2,472,731, dated June 7, 1949 and entitled Ophthalmic Mountings.

One of the principal objects of the invention is to provide a device of the above character which is light in weight, durable and which has its shield or lens supporting parts detachably secured to the shield or lens and located above the useful field of vision of the wearer.

Another object is to provide a device of the above character having a detachable shield or lens portion which may be formed of initially flat sheet plastic material defining two lens portions supported by a reinforcing bar curved to conform substantially to the contour or curvature of the face of the wearer and being of sufficient rigidity to retain the shield or lens substantially to its curvature when said bar and lens are in assembled relation with each other.

Another object of the invention is to provide a device of the above character having a reinforcing bar curved to conform substantially to the curvature of the face of the wearer and a shield or lens portion formed of sheet plastic material defining two lens portions and detachably supported thereby so that it may be replaced by another shield or lens portion of different light transmitting properties when desired or replaced by a similar shield when the original is scratched, broken or otherwise damaged.

Another object is to provide a shield or lens and supporting bar of the above character to which temples may be connected and having an intermediate thickened portion functioning as brow engagement means for retaining the shield or lens properly spaced relative to the eyes of the wearer.

Another object is to provide a shield or lens, formed of sheet plastic material defining two lens portions and having a nasal recess in the lower edge thereof, in combination with a brow engagement and reinforcing bar and a nose engagement member each having a grooved portion adapted to receive an adjacent edge portion of the lens and to be readily detachably secured to said lens by suitable attaching means.

Another object is to provide a reinforcing bar of the above character having a recess and grooves extending longitudinally thereof and adapted to receive adjacent end edge portions of the shield or lens and in which the lens is detachably secured by suitable means.

2

Another object is to provide a brow engagement bar or brace bar of the above character having a recess or channelled portion formed therein for reducing the weight of the bar and for detachably receiving a portion of the shield and allowing flexing thereof while the shield is being fitted to or removed from its assembled position with the brace bar.

Another object is to provide a brace bar of the above character having perforated lug portions adjacent the opposed ends thereof to which temples may be pivotally connected and relatively fixed or integral pins or lugs adjacent the ends and also intermediate the ends for detachably receiving and securing adjacent perforated or apertured portions of the shield or lens in assembled position.

Another object of the invention is to provide a brow engaging or reinforcing bar, a shield or lens and a nose engagement member which are easily and readily attachable or detachable from each other without requiring the use of tools, special equipment or small parts which are difficult to handle and liable to become lost while one lens is being replaced by another.

Other objects and advantages of the invention will become apparent from the following description taken in connection with the accompanying drawings and it will be apparent that many changes may be made in the details of construction and arrangement of parts without departing from the spirit of the invention as expressed in the accompanying claims. The invention therefore is not to be limited to the exact details of construction and arrangement of parts shown and described as the preferred form only has been given by way of illustration.

Referring to the drawings:

Fig. 1 is a front elevational view of the device embodying the invention;

Fig. 2 is a bottom view of the device of Fig. 1 but with nose engagement member removed therefrom;

Fig. 3 is an enlarged sectional view taken on line 3—3 of Fig. 1 and looking in the direction of the arrows;

Fig. 4 is an enlarged fragmentary sectional view showing certain parts of the device of Fig. 1 in assembled position;

Fig. 5 is a front view showing certain parts of the device of Fig. 1 in a partly assembled condition; and

Fig. 6 is a rear elevational and partly sectional view of a portion of a modified form of the device embodying the invention.

Referring more particularly to the drawings wherein like characters of reference designate like parts throughout the several views, the device embodying the invention comprises a sheet of transparent material 5 shaped to provide a pair of integral shield or lens portions 6 and a nasal recess 7 in the lower edge thereof as shown

best in Fig. 1. The said integral shield or lens portions 6 are preferably blanked from sheet plastic material, such as cellulose acetate, methyl methacrylate, or any other known transparent artificial resinous materials or may be formed of sheet plastic material sold under the trade name "Polaroid" and may have any desired light absorbing characteristics or color obtained by using proper light absorbing dyes incorporated within the plastics or artificial resinous material or by incorporating therein means for absorbing in the extra visual regions.

The integral shield or lens portion 6 is provided with an upper curved edge 8 adapted to fit within a pair of relatively narrow laterally spaced slots or recessed seats 9 and a somewhat wider central slot or recess 10 formed longitudinally of a reinforcing bar or support 11. The bar or support 11 may be formed of any suitable material, preferably moldable plastic material, such as for example, cellulose acetate, methyl methacrylate or other known artificial resinous materials or may be formed of cellulose nitrate or the like depending upon the nature of the material used for the shield or lens portion. The sheet material 5 is removably secured within the longitudinal slots or seats 9 and recess 10 by means of detachable connections 12 located near the opposite ends of the bar 11 and by a detachable connection 13 intermediate the ends of the bar. Each connection 12, as best shown in Fig. 4, comprises a relatively fixed or integral pin or lug 14 arranged to extend transversely through an end portion of the bar 11, traversing the slot 9 and thus providing an intermediate bearing portion 14' for engagement by a perforation or slot 15 formed in the lateral or end edge portion of the shield 6. The connection 13 is preferably formed by the provision of a relatively fixed pin or lug 13' secured in and extended through the front wall of the bar 11 and terminating centrally within the recess 10 or by the provision of an equivalent pin or lug formed integrally with or cemented to the bar 11 and extending rearwardly therefrom into said recess. This fixed pin or integral lug is arranged to enter a perforation 13'' in the sheet material 5 near the upper central edge portion thereof.

The support or bar 11 has its front surface preferably curved substantially to the contour shape or curvature of the face of the wearer and is provided with an intermediate or central portion 16 of increased thickness for accommodating the recess 10 and providing a rear surface 17 for engaging the brow of the wearer when in position of use, the bar thus being adapted to space the shield or lens portions 6 from the eyes an amount sufficient to clear the eyelashes of the wearer. The recess 10 is also provided for decreasing the weight of the bar. The said support or bar 11 is provided adjacent its opposed ends with portions 18 tapering outwardly from said intermediate portion and terminating in temple lugs 19 preferably formed of the same material as the support or bar 11, either integrally therewith or separately and joined therewith by a suitable cement, solvent or other adhesive. Suitable temples 20 formed in part or entirely of material similar to the support or bar member 11 are secured to the lugs 19 preferably by hinge members 21 either formed of the same material and integrally with the temples 20, or formed separately and of metal in which instance the said hinge members would be secured to the temples 20 by rivets or the like.

The sheet material 5, in the vicinity of the nasal recess 7, is provided, as best shown in Figs. 1 and 5, with shouldered portions 22 adapted to receive the ends 23 of a detachable nose engagement member 24. The said nose engagement member is shaped substantially to the contour shape of the nasal recess 7 and is provided with a slot 25 to receive an edge 26 of the shield or lens portion adjacent said nasal recess. The nose engagement member 24 may be detachably secured to the shield or lens portion 6 or removed therefrom by slightly pressing the ends 23 toward each other to clear the shoulders 22. The nose member 24 may be formed of the same materials as set forth for said bar 11. The nose engagement member 24 is provided with rearwardly extending integral pad portions 29 for engaging the opposed sides of the nose of the wearer, it being understood that the said pads are suitably angled for proper and comfortable fit with the nose.

It is particularly pointed out that the shield or lens portions 6 are initially formed of flat sheet material and that when detachably secured within the slots 9 and recess 10 of bar 11, the said shield or lens portions are curved to fit within said slots 9 and recess 10 and are retained substantially to said curvature of the slots and the front surface of the recess during the use of the device. The said shield or lens portions may be tinted red, green, or any other desirable color as well as embodying any other absorptive characteristics desired. While the support or bar member 11 is described as being curved substantially to the contour or curvature of the face, the said curvature is also so controlled as to reduce reflection of light incident on the shield or lens portion from a direction rearwardly of the wearer.

The shield or lens portion 6 may be cut, blanked, or otherwise shaped to the contour shape desired from sheet material having the proper characteristics required. In instances when the shield or lens portion 6 is formed of relatively thin material it may be merely bent to the curvature of the bar through the securing thereof within the slots 9 and recess 10 with the bar 11 being solely depended upon for retaining the shield or lens to the desired curvature. In instances when the shield or lens is formed of relatively thick material, the said lens is preferably formed and set, as by heat and pressure, substantially to the said curvature and is then inserted within the slots or seats 9 and recess 10. In this latter instance, the bar 11, of course, aids in retaining the shield or lens portion 6 to said desired curved shape.

When it is desired to assemble the parts of the device of Fig. 1 for use, the upper edge 8 of the shield or lens portion 6 is flexed forwardly to a slightly sharper curvature than it would normally assume when in assembled position so that the opposed lateral or end edge portions of the sheet material 5 may be inserted into the downwardly extending end portions of the slots 9 in the bar 11 and the slots or perforations 15 at the opposite ends of the shield are then partially engaged over the bearing portions 14' of the pins or lugs 14. The major portion of the shield is at such a time slightly forward of the intermediate part of the bar 11 and in order to bring the central portion of the upper edge 8 of the shield into recess 10 it is necessary to flex the center of the shield rearwardly, causing somewhat of a reverse curve at the center of the shield. The shield in this condition is sub-

stantially as shown by Fig. 5 and may then have its upper central portion moved or pressed rearwardly under the adjacent portion of the bar 11 and into the recess 10 rearwardly of the pin 13', this being effected by a combined sliding and pivoting action of the upper outer corners of the shield 6 in engagement with the slotted ends of the bar as the perforations 15 in the shield slip into complete engagement with the bearing surfaces 14' and adjacent parts of the edge 8 slide into the slots 9. When the upper edge 8 is completely within the slots 9 and recess 10, perforation 13' will slip over the end of the pin or lug 13' and the inherent resiliency of the sheet material will spring the upper edge 8 from the dotted position 30 into its normal assembled position shown by full lines in Fig. 2.

The nose member 24 is subsequently engaged with the shield 6 by first slightly flexing the lower ends 23 thereof toward each other to clear the shouldered portions 22 on the lower edge of the shield as the edge 26 is brought into engagement with the slot 25 formed in the nose engagement member 24. When the ends 23 are released they inherently spring outwardly and firmly engage the shoulders 22. It will also be apparent that the bar 11, shield 6 and nose engagement member 24 may as easily be disassembled if desired, such as when desiring to change shields having different light transmitting properties, or when replacing a scratched or damaged shield by a new shield.

A slightly modified form of eye protection device is shown partially in Fig. 6 and embodies a shield or lens portion 6', generally similar to the shield 6 of Fig. 1, but having one of its slotted end portions provided with an elongated slot 31 for slidably receiving a relatively fixed pin 32 mounted in the bar 11'. A groove 9' in the bar 11' for receiving the upper edge portion of the shield 6' is provided adjacent its outer end with a free space 33 for receiving the shield in a manner which will now be described. The bar 11' and the shield 6' are shown in their assembled position and when it is desired to detach the shield from the bar the central portion of the shield is flexed rearwardly sufficiently to free the aperture 13'' therein from the pin 13', such action being similar to that employed for detaching the shield 6 as previously described. However, instead of then using a flexing, pivoting and sliding action to disengage the upper edge and opposite ends of the shield from the bar, the shield 6' is moved or shifted slightly laterally relative to the bar 11' until the end containing the elongated slot 31 occupies the free space 33, and when this occurs the opposite slotted end of the shield will be clear of the associated fixed pin in the bar and may be moved downwardly and out of engagement with the bar 11'. For assembling the shield 6' in the bar or support 11', a reverse procedure may be followed.

Ordinarily, the bar and endpieces, and likewise the nose bearing portion, will be formed as integral members by an injection molding process. The shield or lens portion may be treated with suitable dyes or the like for producing the required absorptive characteristics, color, etc. The bar portion and nose member may be colored to produce any desired effect by brushing or spraying a suitable dye or the like thereon.

From the foregoing description it will be seen that simple, efficient, and economical means have been provided for accomplishing all the objects and advantages of the invention.

Having described the invention, I claim:

1. An ophthalmic device of the character described comprising a bar-like member of relatively stiff material having a front surface curved substantially to the contour of the face of the wearer and having an integral intermediate portion of increased thickness for engaging the wearer's brow, said bar-like member having a recess extending longitudinally thereof and having temple connection means adjacent the opposed ends thereof, a shield-like lens engaged in said recess throughout the major portion of its upper contour edge and having an aperture formed therein, a rearwardly extending relatively fixed lug in said recess extending into said aperture, a slot in said shield-like lens in laterally spaced relation to said aperture, a relatively fixed member carried by said bar-like member and engaging said slot in said shield-like lens for detachably securing said lens in said member, and a nasal recess in the lower edge of said shield-like lens.
2. An ophthalmic device of the character described comprising a bar-like member of relatively stiff material having a front surface curved substantially to the contour of the face of the wearer and having an attachment seat formed therein and extending longitudinally thereof, said bar-like member having temple attachment means adjacent the opposed ends thereof, a shield-like lens having its upper edge detachably secured in said seat, the means for securing said shield-like lens in said seat comprising a relatively fixed lug extending from said bar-like member and passing through an aperture in the shield-like lens and a second relatively fixed lug carried by said bar and spaced laterally from said first lug and detachably engaging a slot in said shield-like lens, and a nasal recess in the lower edge of said shield-like lens.
3. An ophthalmic device of the character described comprising a bar-like member of relatively stiff plastic material having a front surface curved substantially to the contour of the face of the wearer and having a recess forming an attachment seat provided therein and extending longitudinally thereof, said bar-like member having temple attachment means adjacent the opposed ends thereof and having brow engagement means upon its rear surface intermediate said ends, a shield-like lens having its upper edge extending into and detachably secured by suitable means in said recess, the means for securing said shield-like lens in said recess comprising a relatively fixed lug extending from said bar-like member into said recess and passing through an aperture in the shield-like lens and relatively fixed means spaced laterally from said lug and engaging in slots in the peripheral edge of said shield-like lens, and a nasal recess in the lower edge of said shield-like lens, said shield-like lens being curved and maintained substantially to said front surface curvature of said bar-like member.
4. An ophthalmic device of the character described comprising a bar-like member of relatively rigid material having a front surface curved substantially to the contour shape of the wearer's face and having a recess extending longitudinally thereof, said bar-like member having temple attachment means adjacent its opposed ends and having a brow engaging portion on its rear surface intermediate said attachment means, a shield-like lens of flexible

sheet material having its upper edge portion fitting within said longitudinal recess and having a nasal recess in the lower edge thereof, said sheet-like lens, when in operative relation with said bar-like member, conforming substantially to the front surface curvature of said bar-like member, and means for detachably securing said sheet-like lens in said longitudinal recess comprising a normally fixed lug upon an intermediate portion of said bar-like member and extending rearwardly in said recess and an aperture in said lens receiving said lug, said means also comprising slots in said lens in laterally spaced relation to said aperture and normally fixed pins carried by said bar-like member for releasably engaging said slots for securing said lens and bar-like member in operative relation.

5. An ophthalmic device of the character described comprising a bar-like member of relatively rigid non-metallic material shaped in the general direction of the contour of the face of the wearer and having a relatively thick intermediate portion and tapered relatively thinner ends, temple attachment means of substantially the same material adjacent said opposed ends, a brow engagement portion intermediate said temple attachment means on the rear surface of said bar-like member, said bar-like member having an attachment seat extending longitudinally thereof throughout the greater portion of its length and a shield-like lens having the major portion of its upper contour edge positioned in said attachment seat, said upper portion of the lens positioned in the attachment seat having a centrally disposed apertured portion and laterally spaced peripherally slotted portions, said bar-like member having a normally disposed bearing member projecting into said attachment seat and through said apertured portion of the lens and having spaced bearing portions interfitting with the peripherally slotted portions of said lens, the inherent resiliency of the lens releasably maintaining said bearing portions in interfitted relation with the slotted portions of the lens.

6. An ophthalmic mounting of the character described comprising a bar-like member of relatively rigid material shaped in the general direction of the contour of the face of the wearer and having temple attachment means adjacent its opposed ends, said bar-like member having an attachment seat extending in the general direction of the longitudinal axis thereof and a lens of relatively thin resilient sheet material having its upper portion positioned on the attachment seat of said bar-like member so as to extend downwardly before the eyes, said upper portion of the lens having a centrally disposed apertured portion and spaced peripherally slotted portions, and a substantially normally disposed bearing member carried by the bar-like member extending into the attachment seat and through said aperture portion of the lens, said bar-like member having bearing surfaces for detachably engaging said slotted portions of the lens for preventing downward movement of said lens when in assembled position, and with the inherent resiliency of said lens serving to releasably maintain said bearing surfaces of the bar-like member in engaged relation with the slotted portion of the lens.

7. An ophthalmic device of the character described comprising a bar-like member of relatively rigid plastic material having a front sur-

face shaped substantially to the curvature of the face of the wearer and having temple attachment means adjacent the opposite ends thereof, brow engagement means on the rear surface of said member intermediate said temple attachment means, a groove and a relatively wider recess in said bar between said surfaces, lens means of flexible sheet material positioned in said groove and recess so as to extend downwardly before the eyes of the wearer, a relatively fixed lug in said recess extending through an aperture in said lens means, a laterally disposed slot in said lens means spaced laterally from said aperture, and a bearing surface carried by said bar-like member in said groove for detachably engaging said slot, said recess being of such a width as to allow the lens means adjacent said lug to be flexed sufficiently to be disengaged from said lug so that the lens means may be moved laterally relative to said bar-like member when the lens is being disconnected from said bar-like member.

8. An ophthalmic device of the character described comprising a bar-like member of relatively stiff material having a front surface curved substantially to the contour of the face of the wearer and having an attachment seat formed therein and extending longitudinally thereof, said bar-like member having temple attachment means adjacent the opposed ends thereof, a thin resilient shield member having its upper edge detachably secured in said seat, the means for securing said shield member in said seat comprising a recess formed adjacent each end of one of said members and a bearing portion formed adjacent each of the opposed ends of the other of said members and shaped to extend within the respective recesses of said first member, said shield member having a centrally disposed apertured portion adjacent its upper edge and a substantially normally disposed projection member carried by the bar-like member extending into the attachment seat and through said apertured portion of the shield for preventing downward movement of said shield when in assembled position, and with the inherent resiliency of said shield serving to releasably maintain the bearing portions of said other member within the recesses of the first member.
